TELEPHONE SYSTEM

John F. Toomey, New York, N. Y., and Walter E. Hogan, South Boston, Mass., assignors to Bell Telephone Laboratories, Incorporated, New York, N. Y., a corporation of New York

Application March 24, 1933, Serial No. 662,428

22 Claims. (Cl. 179—41)

This invention relates to transmission systems and more particularly to means for controlling the transmission efficiency of such systems.

In telephone toll lines equipped with terminal repeaters, for example, the transmission may be controlled by switching artificial lines into or out of the circuits in order to lower or to raise their transmission levels. These artificial lines are known as pads. This invention relates to means for controlling said pads by means of simplex circuits over the conductors of the operator's cord circuit and the toll lines.

An object of the invention is to control the transmission pad over a simplex circuit without shunting the ringing and signaling currents.

Another object is to control a termination for a transmission line by means of the pad control equipment and to connect said termination across said line when a cord is opened by the operation of a ringing or a splitting key.

Still another object is to connect a pad in each of two lines when a ringing, splitting or talking key of a cord circuit connecting them is operated.

A further object is to disconnect the simplex circuit from the cord circuit when the simplex is not required.

A still further object is to place the pad control equipment at a point remote from the switchboard.

An additional object is to control the pad over tandem trunk circuits.

Other objects will be evident from the specification and claims as set forth below.

A feature of the present invention whereby the above stated objects are attained resides in connecting an arm of the simplex bridge to the tip conductor at each end of the cord circuit and in reversing the tip and ring conductors within the cord circuit.

Another feature resides in connecting battery through the simplex only when both ends of the toll cord are connected to lines of certain character.

An additional feature resides in shunting the pad control relays by a low resistance simplex bridge on certain connections.

A further feature resides in connecting the termination for the transmission line across said line by means of equipment associated with the line whenever a splitting or ringing key is operated.

Still another feature resides in means in the toll cord for disconnecting the simplex circuit on connections where it is not required.

The invention will be understood from the fol-

lowing description, together with the accompanying figures of the drawings in which forms of the invention are illustrated.

Fig. 1 of the drawings shows toll switchboard circuits at a toll center and comprising toll line A arranged for pad control, a tributary toll line B, a toll switching trunk C, a toll tandem trunk D, a toll cord circuit E for interconnecting said lines and trunks, and an operator's telephone circuit F, the circuits being arranged according to the invention to provide pad control on the toll line when required on the various connections.

Fig. 2 of the drawings show combined local and toll switchboard circuits comprising a toll line G arranged for pad control, a tributary toll line H, a trunk or subscriber's line I, a toll cord circuit J, and operator's telephone circuit K, arranged according to a modified form of the invention.

Circuit description

In Fig. 1 the toll line A connecting a distant toll center is provided with a two-way terminal repeater 100 for amplifying the talking and signaling currents passing over the line in either direction. Transmission pad 101 comprising an H-type network shown within the dotted line box is normally inserted in the line. This pad prevents overloading of the repeater 100 and also provides a means for regulating the transmission level of the telephone system in order that an approximately constant talking level will be provided for all types of connections. Connected to the tip and ring talking conductors respectively are relays 102 and 103 whose circuits pass through windings of retardation coil 104. The circuit through these relays and the retardation coil forms a simplex bridge across toll line A. Relays 102 and 103 will operate on battery connected to their respective talking conductors such as may be connected over a simplex circuit from the cord E. Slow release relay 105 will operate in response to the combined operation of relays 102 and 103 and connect a shunt circuit around pad 101 and open the bridge arm of the pad. Terminating network 106 is normally connected across the talking conductors when no cord circuit is connected to the line but is disconnected by the operation of sleeve relay 110 when a cord is connected. It may again be bridged across the line by the operation of relay 102 with relay 103 unoperated. The toll line passes through the usual testboard jacks 107. The repeater, pad and associated pad control equipment may be in the same

office with the switchboard or they may be in an office at a distance. Associated with the terminal is the usual signaling and supervisory equipment. The sleeve cut-off relay 110 is of comparatively low resistance (60 ohms, for example).

Tributary toll line B connecting a small office in the region of the toll center is not provided with transmission pads. The sleeve cut-off relay 114 of this line is of high resistance (500 ohms, for example).

Toll switching trunk C arranged for straightforward operation terminates at the distant end in a plug at a local "B" or trunk switchboard at which appear multiples of subscribers' lines. 15 Trunk C has a high resistance sleeve relay 118 (500 ohms, for example).

Tandem trunk D arranged for straightforward operation terminates at the distant end in a plug 130 at a tandem switchboard at which may appear jacks of toll lines, toll switching trunks and of tandem completing trunks leading to other offices. The jack sleeve relay 125 is of low resistance (57.5 ohms, for example) but normally has a high resistance 126 connected in series 25 with it (442.5 ohms, for example) which is shunted responsive to the connection of the plug 130 at the tandem board with a toll line arranged for pad control.

Cord circuit E has its tip and ring conductors 30 reversed at 131 and is provided with arrangements for controlling the pad control equipment in the toll line on a connection thereto. The cord circuit and associated lines and trunks will be better understood by a description of their 35 operation to be given later.

In Fig. 2, toll line G is similar to toll line A shown in Fig. 1, except that the sleeve relay 210 in line G is of high resistance (500 ohms, for example).

40 Tributary toll line H differs from tributary line B in having a low resistance simplex coil 252 bridged across the talking conductors.

A local subscriber's line or trunk I is also terminated at this switchboard. It has a sleeve relay 45 254 of low resistance (34 ohms, for example).

Cord circuit J has its talking conductors reversed at 231 and, like circuit E has pad control 45 equipment associated with it. These arrangements will be best understood from the following 50 description of their operation.

Operation

When the operator at the distant end of toll 55 line A (Fig. 1) rings over the line, the ringing current operates relay 109 associated with the incoming terminal. Relay 109 closes an operating circuit for relay 112 which locks up under control of cut-off relay 110 and closes a circuit 60 to light lamp 111. At the end of the ringing interval relay 109 releases.

The answering operator noticing the lighted lamp inserts plug 132 of her answering cord into jack 108. Low resistance cut-off relay 110, connected to the sleeve of jack 108 and marginal cord sleeve relay 133 operate over the sleeve circuits of cord and line from battery in the cord sleeve circuit. Relay 110 opens the bridge circuits for relay 109 and termination 106 and the locking circuit for relay 112 releasing the latter which in turn extinguishes the lamp 111. Marginal cord sleeve relay 133 which has operated over the low resistance sleeve circuit, closes its contacts preparing a path for the connecting of battery to the simplex on the cord talking con-

ductors by marginal sleeve relay 134 connected to the sleeve of calling plug 135.

The operator presses talk key 136 connecting her telephone set F to the cord and placing her in talking relation with the calling operator. The path prepared for the simplex circuit is opened at the auxiliary contacts of key 136.

Assuming first that a connection is desired to another toll line which we shall call Aa, identical to line A, the operator releases talk key 136 and 10 inserts calling plug 135 into jack 108a of line Aa (corresponding to jack 108 of line A). Cut-off relay 110a in line Aa and marginal sleeve relay 134 in cord E operate on the current in the sleeve circuit. Sleeve relay 134 connects battery to the 15 previously described path leading through contacts of the answering sleeve relay energizing the simplex circuit connected across the talking conductors of the cord. The simplex circuit, traced from battery passes through front contacts of 20 talk key 136, front contacts of answering sleeve relay 133 then dividing into two branches the first passing through the right-hand winding of impedance coil 137, back contacts of relay 138 to the 25 tip conductor of the answering cord and the second passing through the left-hand winding of the impedance coil, back contacts of relay 139 to the tip conductor of the calling cord. Since the tip and ring cord conductors are reversed at 131 30 within the cord the simplex is bridged across the talking conductors.

Current from the simplex battery, therefore, finds parallel paths over the two talking conductors to the talking conductors of both toll 35 lines. Current flowing out over the tip conductor of line A finds a path to ground through the upper winding of retardation coil 104 and relay 102. Current flowing over the ring conductor passes through the lower winding of coil 104 and 40 relay 103 to ground. Relays 102 and 103 operate closing a circuit for the energization of slow-release relay 105. Relay 105 connects a shunt around the transmission pad 101 and opens the bridge arm of the pad. Pad 101a of line Aa connected to the calling end of the cord is shunted in like manner.

The operator presses ringing key 140 associated with the calling cord thereby connecting ringing current to toll line Aa and opening both 50 talking conductors of the cord between the connecting points for the simplex circuit. Thus, a conductor of the simplex circuit being opened, the simplex can not shunt the ringing current. Battery is thereby disconnected from the ring 55 conductors of both the calling and called lines causing relays 103 and 103a to release. Relays 105 and 105a are thus deenergized and release thereby removing the shunt circuits around the pads 101 and 101a, respectively, and closing the 60 pad bridge arms. Since the tip connected pad control relay 102 remains operated from the simplex battery over the tip side of toll line A, the terminating network 106 is connected across the line, it being connected through front contacts of relay 102 and back contacts of relay 103. The pads in lines A and Aa in this case tend to stabilize the balance of their respective repeaters, and in the case of line A the terminating network 65 106 is also connected across the line to further improve the repeater balance. In the case of line Aa, however, the ground connected to the tip side of the line by the ringing key 140 causes relay 102a to release, thereby opening the 70 75 75

path of terminating network 106a and preventing it from shunting the ringing current.

Upon release of the ringing key, the pads in both lines are again shunted and the termination on line A is removed due to the re-operation of relay 103. After ringing on this type of call, the operator ordinarily does nothing more until she receives a signal to disconnect evidenced by the lighting of one of her cord supervisory lamps. These lamps and their associated relays are not shown in the drawings since they are well known in the art and the drawings would become unnecessarily complicated by their addition.

Supposing, however, that the operator wished to talk to both parties during the connection. She would operate talk key 136 to connect her telephone set. This would open the auxiliary contacts of key 133 thus opening the energizing path for the simplex circuit. This would cause release of the pad control relays in the toll lines reconnecting the pads in both lines during the time her talk key is operated.

If the operator should wish to talk to the distant end of line A and exclude line Aa from the conversation, she would operate talk key 136 and calling cord splitting key 142. The talk key opens the simplex energizing circuit releasing the pad control relays in the lines and splitting key 142 closes at its auxiliary contacts an operating circuit for relay 138, which, in operating opens the simplex lead to the tip of the answering cord and connects battery to the simplex lead extending to the tip of the calling cord. This battery on the tip conductor of line Aa operates relay 102a connecting termination 106a across the line. Thus the pads are reinserted in both lines and a termination is connected across the "held" line. Similarly on talking only to line Aa splitting key 141 is operated instead of 142 and relays 139 and 102 function to connect a termination across line A. Release of the keys removes both pads and the termination. On disconnection removal of one of the plugs reinserts the pads in both lines by de-energizing the simplex.

If tributary toll line B is to be connected to toll line A the operator upon receiving the call over line A releases her talk key 136 and connects plug 135 with jack 115. High resistance cut-off relay 114 operates on the sleeve current, but marginal calling cord sleeve relay 134 does not operate in this high resistance circuit. Battery is not connected to the simplex, therefore, and pad 101 in toll line A remains in the circuit. This is the desired condition on such a connection. The pad control arrangements remain unoperated during the whole connection, except as follows:

Should the operator wish to talk to a party at distant end of tributary line B while excluding line A from the conversational circuit, she would operate her talk key 136 and splitting key 141 associated with her answering cord. Thus terminating network 106 would be connected across line A as previously described. If instead of key 141, key 142 were operated, energizing relay 138, the lead to the tip of the answering cord would be opened and battery would be placed on the tip of the calling cord and line B, but since line B has no pad control or termination circuits nothing would occur thereon. No battery being connected to the tip of line A, the termination would remain disconnected therefrom.

If the operator at the distant end of line A asks for a subscriber in the immediate area of the toll office, the answering toll operator connects her calling cord to toll switching trunk C leading to

the local "B" board at which the line multiple appears. Since the sleeve relay 118 of this trunk is also of high resistance marginal calling cord sleeve relay 134 does not operate in this high resistance circuit. Battery, therefore, is not connected to the simplex and pad 101 in toll line A remains in the circuit. This is the desired condition on such a connection. Sleeve relay 118 connects relay 121 across the trunk. Relays 121 and 122 serve to relay supervisory signals back over the trunk to the toll cord.

The operator presses ringing key 140 causing ringing current to operate A. C. relay 120 in trunk C. Relay 120 operates relay 123 which connects signaling current over the trunk. In this case the operator has kept her talk key operated. When the "B" operator is connected the toll operator gives her the number of the desired line and releases the talk key.

If the call incoming on line A must be routed through a tandem office, the operator connects plug 135 to jack 124 of tandem trunk D. Since the trunk sleeve relay 125 has a high resistance 126 in series with it, marginal cord sleeve relay 134 remains unoperated, while trunk sleeve relay 125 operates lighting lamp 129 at the tandem board. The tandem operator's telephone (not shown) is manually or automatically connected to the trunk and after the toll operator passes the call and releases her talk key, the tandem operator connects plug 130 with a tandem completing trunk or with a toll line or trunk similar to A, B or C of Fig. 1. Assuming that the tandem trunk is connected to a toll line arranged for pad control whose sleeve has a low resistance to ground (60 ohms, for example) as at 143, marginal relay 127 will operate in series with relay 128 and will close a shunt across resistance 126 thus providing a low resistance sleeve circuit at the calling end of cord E and allowing marginal calling cord sleeve relay 134 to operate. Relay 134 energizes the pad control circuit thereby removing pad 101 from the calling line A and in addition energizing the simplex over tandem trunk D to remove the pad in the called toll line whose sleeve is shown at 143. Relay 128 serves to extinguish lamp 129 and place it under control of the release of relay 125.

On a tandem call to a line or trunk not arranged for pad control and therefore having a high resistance (500 ohms, for example) sleeve circuit as shown at 144, marginal relay 127 does not operate with relay 128 and hence does not close a low resistance circuit for marginal relay 134. Under this condition the pad control circuits are not energized and pad 101 remains in line A.

When the tandem operator plugs into either type of line or trunk the control is placed under the toll operator at cord circuit E so that operation of talking, ringing or splitting keys in cord E controls the pads and terminations (when present) of lines outgoing from the tandem switchboard in the same manner as if they were connected directly to cord plug 135.

On disconnection the toll operator disconnects calling and answering cords. Tandem trunk relay 125 releases lighting lamp 129. The tandem operator then removes plug 130 from the jack and relay 128 releases extinguishing the lamp.

In the case of a call incoming on tributary toll line B, the operator inserts answering cord plug 132 into jack 115. Since the line cut-off relay 114 is of high resistance marginal cord sleeve relay 133 does not operate and the simplex remains disconnected on all types of con-

nctions. In case the call is extended by inserting calling cord plug 135 into the jack of toll line A, however, and splitting key 142 is then operated, termination 196 will be connected across line 5 A as will be understood from the previous description.

Referring to Fig. 2, the operator in answering a call incoming on toll line G inserts plug 232 into jack 208. High resistance cut-off relay

- 10 210 and cord sleeve relay 233 operate on the sleeve current. It will be noted that in cord J the answering cord sleeve relay 233 is not marginal, hence will operate on high resistance sleeve circuits. Both relays function as previously described in connection with Fig. 1. The operator presses talk key 236 connecting her telephone set K which includes low resistance simplex bridge 259. Relay 260 operates under control of the talk key.
- 15 20 Assuming first that the call is intended for a second toll line G_g identical to G, the operator releases her talk key 236 and inserts calling plug 235 into jack 208_g of line G_g. Cut-off relay 210_g in line G_g and sleeve relay 234 in cord J operate but marginal sleeve relay 251 in cord J does not operate on the sleeve current. The simplex is thereby energized by relays 233 and 234 in the manner previously described for Fig. 1 and the pad control relays in lines G and G_g operate to remove the pads from the circuit. Operation of the ringing key 240 removes the simplex battery from the ring side of both lines and thereby inserts the pads and terminating network as described for Fig. 1. Upon release of 30 the ringing key, the pads and termination are again removed.
- 35 35 If the operator should press talk key 236 under these conditions, low resistance retardation coil 258, whose mid-point is grounded will form a simplex bridge across the talking conductors. This will effectively shunt the high resistance simplex bridges on the toll lines, such as that on toll line G comprising retardation coil 204 and pad control relays 292 and 293, preventing sufficient current from reaching the pad control relays to hold them operated. The relays in both toll lines will release, therefore, reinserting the pads in the circuit.

- 40 45 If splitting key 242 is operated in this condition, relay 238 operates connecting the simplex lead to the tip of the answering cord through upper contacts of relay 260 which are closed as long as the talk key is operated. The splitting key opens the talking conductors thereby removing the simplex battery from the ring conductor at each end and removing low resistance shunt 250 from the calling cord and called line G_g. Thus battery over the tip of the called line inserts the termination 206_g in the usual manner. The tip relay in the called line is not shunted by bridge 250 over the simplex leads from the tip of the answering cord due to resistance 256 in series with the lead to that cord. The tip relay in the calling line, however, remains shunted by the bridge; hence the termination is not bridged across the calling line to which the telephone set K is connected.
- 50 55 Similarly the operation of splitting key 241 instead of 242, with the talk key operated, connects termination 206 across line G.
- 60 65 On a call to tributary toll line H, calling plug 235 is inserted in jack 215 of line H. High resistance cut-off relay 214 and cord sleeve relay 234 operate and marginal cord sleeve relay 251
- 70 75 remains unoperated, as before. Therefore, the

simplex is connected across the cord and energized. Low resistance simplex bridge 252 connected across the talking conductors of line H, however, effectively shunts the simplex bridge on calling line G comprising coil 204 and the pad control relays. The relays do not receive sufficient current to operate, therefore, and the pads consequently remain in the circuit on this connection. 5

Operation of ringing key 240 removes simplex 10 battery from the ring side of each cord terminal and also removes the low resistance shunt 252 from the answering cord allowing simplex battery on the tip of this cord to pass over line G operating relay 202 thus connecting termination 15 206. Release of the ringing key removes the termination.

Operation of talk key 236 again connects the telephone circuit K and low resistance bridge 250 to the cord and operates relay 260. Operation of splitting key 241 operates relay 239 connecting the simplex battery to the calling cord through the now closed lower contacts of relay 260. Key 241 also removes at its contacts simplex battery from the ring conductor of each 25 end of the cord. Simplex battery on the tip of the answering cord will not be shunted by either low resistance bridge 250 or 252 since the contacts of key 241 are open and resistance 257 is in the lead to the tip of the calling cord. Hence 30 relay 202 in line G operates connecting the termination.

If, instead, splitting key 242 is operated, the bridge 250 shunts the pad control relays leaving the termination disconnected. 35

On a call from line G to a subscriber's line (or trunk) I the operator inserts plug 235 into jack 253 of line I. In this case low resistance cut-off relay 254 associated with line I, cord sleeve relay 234 and marginal cord sleeve relay 251 all operate. Relay 234 energizes the simplex circuit. Marginal relay 251, however, closes a circuit for the operation of relays 238 and 239 which disconnect the simplex from the answering and calling tip conductors, respectively. Relay 251 also 40 connects the talking circuit through repeating coil 255 thereby opening the direct current connection of the talking conductors within the cord while preserving the talking connection. If ringing key 240 is operated, the simplex battery still 45 remains disconnected by relays 238 and 239 so no termination is placed across line G. Line G, in this case, is terminated in the cord circuit in repeating coil 255.

If talk key 236 is operated, relay 260 operates 55 again connecting the simplex to the talking conductors through its contacts and front contacts of relays 238 and 239. Simplex battery on the tip of the answering cord is shunted through bridge 250 in the telephone circuit. If splitting 60 key 241 is operated, the shunt is removed thereby providing the simplex battery on the tip of calling line G to connect the terminating network 206.

On a call from tributary toll line H to subscriber's line (or trunk) I the pad control arrangements are inoperative. 65

Although the invention is shown and described as embodied in certain specific arrangements, applicants do not wish to be limited by such disclosure, but desire to cover broadly all arrangements that come within the spirit and scope of the appended claims. 70

What is claimed is:

1. In a telephone system, a telephone line cir- 75

circuit, a cord circuit adapted to be connected thereto, said cord circuit having its talking conductors reversed between its respective ends thereof, and means to connect a simplex circuit over said line circuit comprising a pair of simplex bridges, one of said bridges being connected across said line circuit, the other said bridge being connected between the tip talking conductor at one end of the cord circuit and the tip talking conductor at the opposite end of said cord circuit.

2. In a telephone system, telephone line circuits, a cord circuit adapted to be connected thereto, the talking conductors of said cord being reversed between the ends thereof, means to connect a simplex circuit to the talking conductors of said line circuits comprising an impedance bridge between the tip talking conductors at opposite ends of the cord circuit and a simplex lead connected to the mid-point of said bridge.

3. In a means to connect a simplex circuit over a telephone line, a line circuit comprising two conductors, a bridge across said line, a simplex lead connected to a middle point of said bridge, a cord circuit adapted to be connected to said line circuit, the tip and ring conductors of said cord circuit being reversed within the cord, a second bridge, a simplex lead connected to a middle point of the second bridge, said bridge being connected between the tip conductors at the opposite ends of the cord circuit.

4. In a telephone system, a transmission line, transmission regulating means associated therewith, a second line, a cord circuit for interconnecting said lines, the talking conductors of the cord circuit being reversed within said cord, a simplex circuit including the talking conductors of said cord circuit and of said transmission line and comprising simplex bridges across said cord circuit and said transmission line, respectively, for controlling said transmission regulating means, the said bridge across said cord circuit being connected between the tip talking conductors at the two ends of the cord.

5. In a communication system, a transmission line, transmission regulating means associated therewith, a cord circuit connected to said line, means for controlling said regulating means comprising a simplex circuit on said line and cord talking conductors, said simplex circuit comprising a bridge connected from the first talking conductor at one end of the cord to the second talking conductor at the opposite end of the cord.

6. In a communication system, a transmission line, transmission regulating means associated therewith, a cord circuit connected to said line, means for controlling said regulating means comprising a simplex circuit on said line and cord talking conductors, means to open both of said cord talking conductors, means to de-energize one side of said simplex responsive to the operation of said last means consisting of the connection of the simplex circuit to one of the cord talking conductors at one end of the cord and to the other at the opposite end of the cord.

7. In a communication system, a transmission line, a cord circuit connected thereto, means to signal over said line comprising means in said cord circuit to open said talking conductors and to apply signaling currents across said conductors between said opening and said line, and means to connect a bridge across the talking conductors of said cord circuit without shunting said signaling currents comprising connections for said bridge from the first talking conductor at

one end of said cord to the second talking conductor at the opposite end of said cord.

8. In a telephone system, a pair of telephone lines, transmission pads normally connected in each of said lines, a cord circuit for interconnecting said lines, and pad control means to effectively remove the pads from both said lines responsive only to the connection of the cord circuit between said lines.

9. In a telephone system according to claim 8, talking and ringing keys within said cord circuit, said pad control means reinserting both of said pads on operation of any one of said keys.

10. In a telephone system according to claim 8, a splitting key associated with each end of said cord circuit, said pad control means reinserting both said pads on operation of either of said keys.

11. In a telephone system according to claim 8, a splitting key associated with each end of said cord circuit, a terminating network associated with each said line, said pad control means connecting the terminating network associated with a first of said lines across said line responsive to the operation of the splitting key associated with the end of the cord circuit connected to said line.

12. In a telephone system, telephone lines, transmission pads in said lines, a cord circuit adapted to interconnect said lines, answering and calling sleeve relays in said cord circuit, and pad control means comprising a simplex circuit adapted to be connected to said cord circuit responsive to the operation of both said sleeve relays.

13. In a telephone system, a switchboard, a transmission line terminating thereat, transmission regulating means associated with said line, other lines of a first and also of a second character also terminating at the switchboard, a cord circuit for connecting said transmission line with any one of said associated lines of either character, a simplex circuit comprising the talking conductors of said cord circuit and of said transmission line for controlling said transmission regulating means, and means responsive to the connection of said cord circuit to said transmission line and a line of said first character only to control said transmission regulating means over said simplex circuit.

14. In a telephone system, a switchboard, a transmission line terminating thereat, transmission regulating means associated with said line, other lines of a first and also of a second character also terminating at the switchboard, a cord circuit for connecting said transmission line with any one of said associated lines of either character, a simplex circuit including the talking conductors of said cord circuit and of said transmission line for controlling said transmission regulating means, and means responsive to the connection of said cord circuit to said transmission line and a line of said first character only to energize said simplex circuit and control said transmission regulating means.

15. In a telephone system, a transmission line, transmission regulating means associated therewith, a terminating network also associated therewith, a second line, a cord circuit for interconnecting said lines, a simplex circuit including the talking conductors of said cord circuit and of said transmission line and comprising simplex bridges across said cord circuit and said transmission line, respectively, for controlling said transmission regulating means, and means for controlling said terminating network comprising one of the talking conductors of said cord circuit and of said transmission line and one-half of the

simplex bridges in said cord and line, respectively.

16. In a telephone system, a transmission line, transmission regulating means associated therewith, a terminating network also associated therewith, a second line, a cord circuit for interconnecting said lines, a simplex circuit including the talking conductors of said cord circuit and of said transmission line for controlling said transmission regulating means, means responsive to the operation of a splitting key in any part of said cord circuit to open one of the talking conductors included in said simplex circuit to remove control of said transmission regulating means and to control said terminating network over the remaining talking conductor.

17. In a telephone system, a trunk circuit, a cord circuit connected to one end of said trunk circuit, a telephone line connected to the other end of said trunk circuit, transmission pads normally connected in said telephone line, and pad control means for controlling said pads from said cord circuit comprising a simplex circuit on the talking conductors of said cord, trunk and line circuits.

18. In a telephone system, a telephone line, transmission regulating means associated with said line, a cord circuit connected to said line, an operator's telephone set adapted to be connected to said cord circuit, means comprising a simplex circuit on the talking conductors of said line and cord circuits to control said transmission regulating means, and a low resistance simplex bridge connected across said operator's telephone set to effectively shunt the simplex circuit on said line when said telephone set is connected to said cord circuit.

19. In a telephone system, a switchboard, a transmission line terminating thereat, transmission regulating means associated with said line, other lines of a first and also of a second character also terminating at the switchboard, a cord circuit for connecting said transmission line with any one of said associated lines of either char-

acter, a simplex circuit including the talking conductors of said cord circuit and of said transmission line and comprising simplex bridges across said cord circuit and said transmission line, respectively, for controlling said transmission regulating means, means responsive to the connection of said cord circuit to said transmission line and a line of either character to energize said simplex circuit, and a low resistance simplex bridge across each line of said second character to shunt the simplex circuit from said cord circuit to said transmission line and prevent control of said transmission regulating means on connections to lines of said second character.

20. In a telephone system, a telephone line, a transmission pad in said line, a terminating network adapted to be connected across said line, a cord circuit connected to said line, pad control means comprising a simplex circuit on the talking conductors of said line and cord circuit, and means for controlling said terminating network comprising one side of said simplex circuit.

21. In a telephone system, a telephone line circuit, transmission regulating means associated therewith, a cord circuit, means associated with said cord for controlling said transmission regulating means, a trunk circuit adapted to interconnect said cord and line circuits, and means to render said cord circuit means effective responsive to the connection of said trunk between said cord and line circuits.

22. In a telephone system, a telephone line, a terminating network normally connected across said line, a cord circuit, means to disconnect said terminating network responsive to the connection of said line and cord circuits, and means responsive to the operation of a ringing or splitting key in said cord circuit while connected to said line circuit to reconnect said network across said line.
